Patented Dec. 13, 1927.

UNITED STATES PATENT OFFICE.

ALBERT HOMER CANFIELD, OF BRIDGEPORT, CONNECTICUT.

TANK VALVE.

Application filed January 30, 1924, Serial No. 689,491. Renewed June 9, 1925.

This invention pertains to an improved tank valve, the construction and advantages of which will be hereinafter set forth, reference being had to the annexed drawings 5 wherein:

Fig. 1 is a perspective view of the valve;
Fig. 2 a vertical sectional view thereof;

Fig. 3 a similar view illustrating the form 10 the valve takes when it is seated and subjected to the pressure of the water above the same within the tank, and

Fig. 4 a sectional view illustrating a slightly modified form.

The main object of the invention is to produce a durable valve, and one which, by reason of its construction and consequent action under the pressure of the water, will readily seat itself and closely conform to its seat thereby ensuring stoppage of the flow 20 of water. The construction, moreover, is such that ball of given size will function with seats of different dimensions, a point of manifest advantage.

Again, by reason of its construction, the 25 ball will not collapse under pressure and, furthermore, will travel down with the falling water level until such level reaches a point quite near the bottom of the tank.

With these and other objects and advantages in view, reference will first be made to the construction shown in Figs. 1 to 3.

The lower portion of the ball denoted by 1 is generally hemispherical in form having an opening 2 in its lower end as is usual 35 in valves of this type. The wall preferably thickens as it extends upwardly from the opening and at its upper portion the outer face flares or curves outwardly as at 3. The inner face of the wall curves inwardly as at 4, said curved portion being continued inwardly, forming the inner face 40 of the top 5, and terminating in a downwardly curved section 6, thereby forming a downwardly projecting enlargement or 45 post-like member 7 centrally of the ball.

The portion of the ball thus far described is produced from flexible or readily yielding stock so that it will readily conform to the valve seat and any inequalities therein.

50 The upper portion or layer of the top is produced from stock, which, when subjected to the vulcanizing process, becomes relatively rigid, the superimposed layers becoming of course an integral structure under the 55 vulcanizing action. The different grades of stock are indicated in the sectional views

by varied hatch lines, the heavier lines indicating the harder stock.

Extending upwardly from the center of the top is a stem 8, in which is embedded 60 the usual spud 9 for attachment of the valve lifting and guiding wire commonly employed with valves of this type.

The upper face of the top is preferably 65 stiffened in zones or lines and this is preferably accomplished by providing stiffening elements shown in the present instance as a series of concentric annular spaced ribs 10 produced in the process of molding the 70 valve.

This concentric formation is preferred, though I do not wish to be limited thereto as the ribs might be otherwise positioned.

From the foregoing it will be seen that I have produced a one piece ball having a 75 flexible lower valve contacting portion and a relatively rigid top having a substantially flat upper face while the inner face is arched from its sides toward the center. When seated and subjected to the pressure of the 80 water within the tank upon its top, the ball assumes the form shown in Fig. 3. From an inspection of this figure it will be seen that the lower portion of the ball is somewhat flattened and is bulged outwardly, this being due to the pressure exerted by the water overlying the substantially rigid top 5 which forces the valve evenly and fully to its seat. Inasmuch as the top is 85 thicker at its middle and at its outer portions than it is intermediate said portions, it may bow down slightly at the center as shown in Fig. 3 when subjected to the seating pressure of the water. Such yielding, however, is not detrimental but on the contrary, appears to be beneficial in securing 90 a proper seating of the valve.

In Fig. 4 a slight modification of the structure is illustrated.

In this instance the upwardly extending 100 stem 8 is dispensed with and the spud is secured in the centrally disposed inwardly projecting post or enlargement designated by 7^a. As indicated in the drawing, the post may be produced from hard curing stock.

105 What I claim is:

1. A hollow tank valve having a substantially hemispherical lower portion formed from flexible stock and a relatively rigid closed flat top formed as a continuation of 110 the lower portion.

2. A tank valve having a substantially

- hemispherical lower portion formed from flexible stock; a relatively rigid flat top; and a series of ribs formed on the top.
3. A tank valve having a substantially hemispherical lower portion formed from flexible stock; a relatively rigid flat top; and a series of concentric ribs formed on the top.
4. A tank valve having a substantially hemispherical flexible lower portion; and a relatively rigid flat top, the inner wall of the lower portion merging into the inner wall of the top upon a curve to produce an arched formation.
5. A tank valve having a substantially hemispherical flexible lower portion; and a relatively rigid flat top, the inner wall of the lower portion merging into the inner wall of the top upon a reversely curved line extending toward the center of the top whereby a central post or extension is produced upon the inner face of the top.
6. A tank valve having a substantially hemispherical flexible lower portion; a relatively rigid flat top; a post extending upwardly from the top; and a spud secured in the outer end of the post.
7. A tank valve having a substantially hemispherical flexible lower portion; a relatively rigid flat top; a post extending upwardly from the top; a spud secured in the outer end of the post and a series of ribs formed upon the outer face of the top.
8. A tank valve having a substantially hemispherical flexible lower portion; and a relatively rigid flat top, the wall of the valve being materially thickened at the point of emergence of the top and the lower portion.
9. A tank valve having a substantially hemispherical flexible lower portion; and a relatively rigid flat top, the outer face of the lower portion, at the upper part thereof, flaring outwardly.
10. A tank valve having a substantially hemispherical flexible lower portion; and a relatively rigid flat top, the upper part of the wall of the lower portion where it merges into the top having its outer face curved outwardly and its inner face curved inwardly.
11. A tank valve having a jointless body comprising a substantially hemispherical lower portion and a relatively rigid top, the outer wall of the ball flaring outwardly and the inner face inwardly, the ball being materially thickened thereby at the point of emergence of the top and the lower portion.
12. A tank valve having a substantially hemispherical yielding lower portion and a relatively rigid top, the wall of the valve being materially thickened at the point of emergence of the top and the lower portion, and the wall of the top between the thickened portion and its center being somewhat thinner to produce a zone of flexure.
13. A tank valve having a substantially hemispherical yielding lower portion and a relatively rigid top, the wall of the valve being materially thickened at the point of emergence of the top and the lower portion, and the wall of the top between the thickened portion and its center being somewhat thinner to produce a zone of flexure, and a spud stem extending upwardly from the center of the top.
14. A tank ball having a jointless body comprising a top and a lower relatively soft valve seating section, the upper portion of the outer face of said section flaring outwardly and the inner wall of the ball at the emergence of the top and lower section being in-curved toward the center of the top to produce a relatively thickened portion at such point of emergence.

In testimony whereof I have signed my name to this specification.

ALBERT HOMER CANFIELD.
